UNITED STATES PATENT OFFICE.

MARTIN DONELSON, OF MEMPHIS, TENNESSEE.

SUTURE INSTRUMENT.

Application filed June 8, 1921. Serial No. 476,061.

To all whom it may concern:

Be it known that I, MARTIN DONELSON, a citizen of the United States, residing at Memphis, in the county of Shelby and State 5 of Tennessee, have invented certain new and useful Improvements in a Suture Instrument; and I do hereby declare the following to be a full, clear, and exact description of the invention, such as will enable others 10 skilled in the art to which it appertains to make and use the same.

The invention relates to an article designed for general application in suture work and intended more particularly for 15 surgical operations.

Other objects and advantages will be apparent and suggest themselves as the nature of the invention is understood.

While the drawings illustrate an embodiment of the invention it is to be understood 20 that in adapting the same to meet different conditions and requirements, various changes in the form, proportion and minor details of construction may be resorted to 25 without departing from the nature of the invention.

Referring to the accompanying drawing forming a part of the specification,

Figure 1 is a top plan view of an instrument embodying the invention, the needle 30 being reversed and housed.

Figure 2 is an end view of the instrument adapted for service and having parts broken away.

Figure 3 is a section on the line $x-x$ of Figure 2 looking to the right as indicated by the arrows, and

Figure 4 shows some of the various 40 stitches adapted to be formed by the use of the instrument.

Corresponding and like parts are referred to in the following description and designated in the several views of the drawing by like reference characters.

The instrument embodies a handle 1 which 45 may be of any construction and design. An extension 2 at the forward end of the handle and in line therewith constitutes a holder for the needle and is provided with an opening 3 in which the needle is received. A set 50 screw 4 threaded in an opening formed in a side of the extension 2 is adapted to secure the needle 5 in the required adjusted position. The opening 3 is of a depth to provide 55 a housing for the needle 5 as indicated most clearly in Figure 1. When not required for

immediate service the needle 5 is reversed and its pointed end inserted in the opening 3 for protection. It should be stated that any type or form of needle may be employed depending upon the particular work 60 at hand.

A box or container 6 is provided at one side of the handle 1 adjacent the inner end of the extension 2 and is closed by means 65 of a cover 7 which is held in place by means of a retainer 8. The retainer 8 consists of a ring or band having an inner beveled flange 9 which overlaps the edge portion of the cover 7. The outer portion of the box 70 or container 6 is reduced and externally screw threaded and receives the retainer 8 which is correspondingly threaded. A slot 10 is formed in the forward side of the box 75 or container 6 for the passage of the thread 11. The cover 7 is flexible and preferably is confined between the flange 9 and the outer end of the box or container 6. By reason of the flexibility of the cover 7 its middle portion may be pressed inwardly to admit 80 of the cover being used in the capacity of a brake.

A spool or bobbin 12 is disposed within the box or container 6 and the thread 11 is wound thereon. In the preferable construction 85 the spool or bobbin 12 is of a size to fit snugly within the container 6 to obviate binding and prevent the thread from lodging between the head of the spool and the inner wall of the container. When the cover 90 7 is removed the spool 12 may be placed in position or removed from the container 6 as required. The slot 10 provides a passage for the thread 11.

When the instrument is not required for 95 immediate service the thread 11 is completely wound upon the spool 12 so as not to project from the container 6 and the needle 5 is reversed with its pointed end housed in the opening 3 of the extension 2. 100 When the instrument is adapted for service the needle 5 is secured in the opening 3 of the extension 2 by means of the set screw 4 with its pointed end outward and the thread 11 has its end portion withdrawn or 105 unwound from the spool 12 and passed through the slot 10 and the eye of the needle 5 as indicated in Figure 2. When the instrument is in operation unwinding of the 110 thread from the spool is prevented or controlled by applying pressure to the central portion of the cover 7 which is caused to

offer a greater or less resistance to the rotation of the spool 12 according to the degree of pressure exerted thereon as will be readily understood. For surgical operations the parts are sterilized but for ordinary use sterilization is not necessary. The construction is such as to permit of the container 6 and extension 2 forming a part of the handle 1, said parts being cast or formed in any manner. Except when intended for surgical use the cover 7 is not necessary—the ball of the thumb acting directly on the reel as a brake. For surgical purposes the function of the cover is to render the container water tight, except the small hole left for the exit of thread, and to prevent contamination of thread.

The extension 2 is offset to elevate the needle and prevent its contact with the surface upon which the instrument may be temporarily placed when both hands of the surgeon are otherwise occupied.

For surgical operations the stitches may be placed without being touched by the hand, a pair of usual dressing forceps manipulating the thread in conjunction with the needle. The construction is such that the needle, thread and forceps may be sterilized. The spool of thread is completely enclosed and protected. A disc 13 of metal or other material may be interposed between the cover 7 and the spool 12 to insure a uniform braking action.

The instrument admits of a variety of stitches being formed some of which are indicated in Figure 4, the first in order being the ordinary lock stitch, the shuttle or lock thread being straight. The second repre-

sents a lock stitch, the stitches being formed by passing the needle through from opposite sides in alternation and crossing the shuttle or lock thread over the suture. The third is the well known chain stitch. The fourth is a crossed chain stitch the needle being passed through from opposite sides in alternation. The fifth is an overcast chain stitch. The sixth is a variety of chain stitch the loops being spread by a peculiar placing of the stitches with reference thereto.

Having thus described the invention, what I claim is:

In a suture instrument, a handle from which the needle is adapted to extend, a container on the handle for a spool of thread to be supplied to the needle, said container being open at the outer end to facilitate insertion and removal of the spool, the container having a thread guide opening therethrough, a flexible cover resting on said outer end of the container and adapted to be depressed to function as a brake to retard rotation of the spool as the thread is paid out, a retainer fitted to the container having an opening so that a finger of the operator may engage the said cover, the retainer having an inwardly extending flange about the opening to overlap the marginal edge portion of the cover to clamp it against said end of the container.

In testimony whereof I affix my signature in presence of two witnesses.

MARTIN DONELSON.
